PROCESS FOR PRODUCING ACETYLENE

Paul W. Garbo, Freeport, N. Y., assignor to Hydrocarbon Research, Inc., New York, N. Y., a corporation of New Jersey

Application November 15, 1951, Serial No. 256,576

5 Claims. (Cl. 260—679)

1

This invention relates to an improvement in the production of acetylene by the partial combustion of a hydrocarbon. More particularly, it discloses a novel method for rapidly cooling acetylene-containing gas produced by partial combustion of a hydrocarbon gas.

Acetylene is produced by the high temperature-short contact time partial combustion of a hydrocarbon such as methane; generally temperatures between 2500° and 3000° F. and contact times between 0.001 and 0.1 second are suitable for the production of acetylene by the partial combustion of a hydrocarbon. It is known that it is necessary to cool the acetylene-containing product gas as quickly as possible after the partial combustion in order to minimize decomposition or other undesired reaction of the thermally unstable acetylene. Various procedures have been suggested to accomplish the quenching of the acetylene-containing product gas. One of the most efficient procedures for quenching the product gas involves contact of the product gas with cool, finely divided particles of thermally absorptive materials such as alumina, silica, metallic aluminum, etc. The introduction of finely divided particles of a heat carrier into the acetylene-containing product stream is an efficient means of quenching because of the heat capacity and heat transmission properties of the particulate solid. The process of the subject invention is substantially more efficient than previously known methods for cooling acetylene-containing gas produced by partial combustion of a hydrocarbon.

In accordance with the process of this invention, quenching of acetylene-containing gas produced by the partial combustion of a hydrocarbon, preferably a gaseous hydrocarbon such as methane, is effected by the introduction of finely divided particles of a higher iron oxide (such as Fe_2O_3 and Fe_3O_4) into the gas produced by partial combustion of the hydrocarbon generally at a temperature between 2500° to 3000° F. and at a contact time between 0.001 and 0.1 second. Contact of the hot product gas with finely divided particles of the higher iron oxide which are at a relatively low temperature, say not more than 600° F., effects rapid and efficient cooling of the product gas to a temperature below about 800° F.; ordinarily, the product gas is cooled to a temperature between about 650° and 750° F. by the introduction of the higher iron oxide therein. The superiority of the process of this invention for quenching acetylene-containing product gas is attributable to the fact that the

2

conventional sensible-heat cooling and heat exchange effected by a finely divided solid are supplemented materially by the endothermic reduction of the higher iron oxide to a lower oxide (not lower than FeO). The solid quench material may be entrained in the product gas and readily separated therefrom by conventional means such as cyclone separators.

A significant advantage of the process of the invention is that the concentration of the acetylene in the cooled gas is substantially increased as a consequence of the reduction of the higher iron oxide by the hydrogen and carbon monoxide present in the product gas. The acetylene content on a dry basis of the gas quenched by the process of this invention may be as high as 12 to 14 per cent by volume which compares very favorably with 8 to 9 per cent acetylene content of the same gas quenched by conventional means.

The lower iron oxide produced during the quenching of acetylene-containing gas may be re-oxidized with air or oxygen to form the higher oxide of iron and then recycled, after cooling to a temperature below about 600° F., to the quench zone. Reoxidation of the used quench material to a higher iron oxide is an exothermic reaction and the heat liberated therein can be used in the heating of the methane or other hydrocarbon and oxygen streams prior to their combination for production of acetylene by partial combustion. The recycle operation involving oxidation of the quench material and recycle of iron oxide in a higher state of oxidation to the quenching zone is a self-contained unitary process which provides the most efficient means yet devised for the quenching of a hot acetylene-containing gas.

While ferric oxide (Fe_2O_3) and magnetite (Fe_3O_4 -ferrosoferric oxide) may be employed as the higher iron oxide in the process of the invention, magnetite is the preferred material. The quenching capacity of magnetite is approximately twice that of ferric oxide. In the further description of the invention, magnetite will be employed as the quench material.

The partial combustion process for the production of acetylene is ordinarily carried out at atmospheric pressure. The ratio of atoms of oxygen to atoms of carbon, termed the O/C ratio, in the feed gases, is usually in the range of 1.1 to 1.3. In the typical operation, the product of the partial combustion comprises on a volume basis (all moisture having been removed) approximately 8 per cent acetylene, 25 per cent carbon monoxide, 55 per cent hydrogen, 5 per cent carbon dioxide and 5 per cent unconverted methane.

The partial combustion product gas issuing from the reaction zone desirably at a temperature of approximately 2800° F. is immediately contacted with magnetite particles; generally the particle sizes fall predominantly in the range of 100 to 200 mesh. The magnetite particles are usually introduced into the quench zone at a temperature between 450° and 600° F.

The temperature of the acetylene-containing gas is quickly dropped to below 800° F. by contact 10 with the cool particles of magnetite. The cooling effect of the magnetite particles is principally attributable to two factors, namely, the absorption of sensible heat by the solid particles and the endothermic reduction of magnetite to ferrous oxide by the hydrogen present in the acetylene-containing product gas. In a fraction of a second, ordinarily less than 0.1 second, the product gas is cooled to a temperature in the range 20 of about 650° to 750° F. by the process of the invention.

Quenching of the product gas is generally effected by the use of 0.2 to 2.0 pounds of iron oxide per cubic foot of product gas issuing from the combustion zone. In most cases, not more 25 than 1.0 pound of iron oxide per cubic foot of product gas will suffice.

The solid particles which have been partly reduced are readily separated from the cooled product gas by conventional means for separating 30 solids from gases. In the preferred modification of the invention involving oxidation of the separated, partly reduced heat carrier to a higher iron oxide and its recycle to the quenching zone, the oxidation may be effected with air or oxygen 35 at temperatures in the range of 800° to 1200° F. Steam may be added during the air or oxygen oxidation. The ferric oxide or magnetite formed by the oxidation is cooled to a temperature below 40 about 600° F. and recycled to the quench zone.

In the accompanying drawing there is diagrammatically illustrated the process of this invention for quenching acetylene-containing product gas employing magnetite as the quench material.

Natural gas which has been preheated to a 45 temperature of about 1000° F. is introduced through a pipe 1 into a burner 2 which effects intimate mixing of the natural gas with oxygen which has been preheated to a temperature of about 400° F. and which is introduced into the burner 2 through a pipe 3. The O/C ratio of the mixture of natural gas and oxygen introduced into the burner 2 is in the range of 1.1 to 1.3. In the combustion zone 4 natural gas and oxygen are reacted at a temperature of about 2800° F., 50 at atmospheric pressure and at a contact time preferably in the range of 0.001 to 0.01 second to yield a product gas comprising approximately 8 per cent by volume (dry basis) of acetylene.

The product gas at reaction temperature issues 55 from the combustion zone 4 through the constricted passage 5 into a quench zone 6. In the quench zone 6 the product gas is contacted with powdered magnetite of predominantly 100 to 200 mesh particle size which at a temperature of about 600° F. is introduced through the entry ducts 8 and 9 into the quench zone 6. Contact of the hot product gas with the cool powdered magnetite results in the cooling of the product gas to a 65 temperature of about 650° to 750° F. in less than 0.1 second.

The particulate solid which is partly converted to ferrous oxide is entrained in the product gas and is carried out of the quenching zone 6 through 70 the conduit 10 which leads to a gas-solid sepa-

rator 12. The solid particles are separated from the product gas in the separator 12 and are removed therefrom through a pipe 14.

The product gas removed from the separator 12 through a pipe 15 is sent to a recovery system wherein the acetylene is separated from the other components of the gas. The recovery of acetylene from the product gas is not a part of the process of this invention and there are a number of well-known procedures for effecting separation of acetylene from the CO, H₂, CO₂ and CH₄ components of the product gas.

The partly reduced particles separated from the product gas are introduced through the pipe 14 into a roaster 17 wherein they are oxidized to ferric oxide and magnetite with air, desirably at a temperature of 800° to 1200° F. Air which has been preheated to a temperature of about 500° F. is introduced through a pipe 20, a blower 21 and a pipe 23 into the roaster 17. The heat liberated during the exothermic oxidation of ferrous oxide to ferric oxide and magnetite can be used for preheating the air introduced into the roaster or the natural gas and oxygen which are partially burned to yield acetylene. The waste gas from which heat can be recovered issues from the roaster 17 through a pipe 25.

The higher oxide of iron is withdrawn from the roaster 17 through a pipe 27, cooled in exchanger 28 to a temperature of about 600° F., and is then passed through pipes 29 and 30 to the entry ducts 8 and 9 and thence into quench zone 6.

The process of the invention is illustrated in the following example wherein the acetylene-containing product gas is cooled by contact with magnetite.

10,000 cubic feet of natural gas and 6,200 cubic feet of oxygen (approximately 96% by volume purity) measured at standard conditions are charged hourly to a reaction zone wherein they undergo partial combustion at a temperature of about 2800° F. to form 23,800 cubic feet of gas having the following approximate volume composition:

	Per cent
Hydrogen	38
Water	25
Carbon monoxide	21
Acetylene	6
Methane	3.5
Carbon dioxide	2.8
Others	3.7

This gas is cooled to 700° F. by the use of 12,000 lbs. of magnetite introduced hourly into the quench zone. The magnetite is partly reduced to ferrous oxide during the quenching operation. While on a dry basis the acetylene content of the product gas is 8% by volume, after the quenching operation because of the loss of hydrogen in the partial reduction of the magnetite the quenched gas on a dry basis has an acetylene content of 12.3% by volume.

Thus, it will be observed that quenching of the product gas with magnetite not only effects superior cooling of the product gas but also effects a substantial increase in the acetylene concentration of the product gas, thereby facilitating the subsequent isolation of acetylene from the product gas.

It is apparent that the process of this invention provides an efficient, simple process for quenching acetylene-containing gas produced by the partial combustion of a hydrocarbon. The

cyclic operation whereby the ferrous oxide produced during the quenching is oxidized and returned to the quenching zone requires a minimum of steps.

Obviously, many modifications and variations of the invention as hereinabove set forth may be made without departing from the spirit and scope thereof, and therefore only such limitations should be imposed as are indicated in the appended claims.

I claim:

1. In the production of acetylene by partial combustion of a hydrocarbon with oxygen at a temperature above about 2,500° F., the improvement which comprises quenching the acetylene-containing product gas at said temperature by contact with particles consisting of iron oxides predominantly in a higher state of oxidation than ferrous oxide in an amount in the range of from 0.2 to 2 pounds of said solid particles per cubic foot of said product gas, said solid particles having a temperature of not more than about 600° F. and a size range predominantly in the range of 100 to 200 mesh whereby the temperature of said product gas is reduced to a temperature below about 800° F. with concomitant partial reduction of said higher oxide to a lower oxide not lower than ferrous oxide.

2. The method according to claim 1 wherein said solid particles introduced into contact with said product gas have a temperature of not less than about 450° F.

3. The method according to claim 1 wherein said higher oxide of iron is predominantly magnetite and the lower oxide is ferrous oxide.

4. In the production of acetylene by partial combustion of a hydrocarbon with oxygen at a temperature above about 2,500° F., the improvement which comprises quenching the acetylene-containing product gas at said temperature by contact with particles consisting of iron oxides predominantly in a higher state of oxidation than ferrous oxide in an amount in the range of from 0.2 to 2 pounds of said solid particles per cubic foot of said product gas, said solid particles having a temperature of not more than about 600° F. and a size range predominantly in the range of 100 to 200 mesh whereby simultaneously cooling said product gas to a temperature below about 800° F. and reducing said higher oxide of iron to a lower oxide not lower than ferrous oxide, separating solid particles comprising ferrous oxide from the quenched product gas, re-oxidizing said ferrous oxide in said separated particles to a higher oxide of iron, and thereafter returning said particles to said quenching step.

5. The method according to claim 4 wherein said solid particles introduced into contact with said product gas have a temperature of not less than about 450° F.
